UNITED STATES PATENT OFFICE.

ERNST C. F. BARTH, OF PHILADELPHIA, PENNSYLVANIA.

WINDOW-SCREEN.

SPECIFICATION forming part of Letters Patent No. 651,097, dated June 5, 1900.

Application filed March 10, 1899. Serial No. 708,568. (No model.)

To all whom it may concern:

Be it known that I, ERNST C. F. BARTH, a subject of the Emperor of Germany, residing at Philadelphia, in the county of Philadelphia 5 and State of Pennsylvania, have invented certain new and useful Improvements in Window-Screens; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to improvements in window-screens, and more particularly to that class of screens which are adapted to fit the frame of the window, thereby offering no obstruction in raising or lowering the sash for 20 ventilation or other purposes.

The object of the invention is to provide a screen of this character which is adjustable to any window and in which the screen-netting is wound on a spring-actuated roller, 25 somewhat after the fashion of an ordinary window-shade.

The several novel features of construction and combination of parts will hereinafter be more fully described, and defined in the claim 30 appended, reference being had to the accompanying drawings, in which similar numerals designate similar parts in the several views.

Figure 1 is a view of a window-frame with my improved screen attached thereto and 35 showing the screen-netting partly drawn. Fig. 2 is a detail view of part of the screen-netting. Fig. 3 is a cross-section of one of the standards. Fig. 4 is a detail view with 40 a portion of the standard cut away, showing the adjustable bracket.

The window is designated by the numeral 1, in which is fitted the screen. The screen consists of standards 2, secured to the window-frame by any suitable means. In this case I 45 employ a metal brace 12, one end of which is secured to the window-frame and the other to the standard, spring-roller 3, to which is mounted the screen-netting 4, the same being reinforced by the rod 5. Into the upper end 50 of each standard is adjustably secured a bracket furnishing a journaling for the roller 3. The brackets are each provided with a

clamping-bolt 10, which passes through the slot 6 in each standard, and the bracket is clamped by a suitable thumb-piece 11. The 55 standards 2 are each provided with a longitudinal slot 7, which extends the entire length thereof and into which the edge of the screen is adapted to pass. To obtain a more efficient and satisfactory screen, the slot in each 60 standard is furnished with a plurality of grooves 8, which individually are intended to form a passage or path for the reinforcing rope or strip 9 on the screen-netting. In order to facilitate the rolling of the screen, the 65 strips 9 do not extend the entire length of the same, yet are long enough to possess sufficient bearing in the grooves to hold the screen firmly, so as to prevent displacement by wind, accident, &c.

70 It is obvious that a window-screen as above described is operated much after the manner of an ordinary window-shade, and in adjusting it to the frame of the window it is necessary first to select the proper groove in the 75 longitudinal slot for the passage of the rope or strip, after which the brackets are adjusted for the roller, and then, finally, the standards are secured to the frame of the window.

I desire to have it understood that such 80 changes as are within the spirit of my invention I still reserve and do not limit myself by the above description.

Having thus described my invention, what I claim as new, and desire to secure by Letters 85 Patent, is—

An improved window-screen consisting of two standards, adjustable brackets at the upper ends of the standards, a spring-actuated roller journaled in the brackets, a screen secured to the roller, longitudinal slots in the standards, a plurality of grooves communicating with each slot, strips corresponding to and adapted to fit in said grooves secured to the screen-netting, whereby the netting is securely held in place and guided in operation, substantially as described.

In testimony whereof I affix my signature in presence of two witnesses.

ERNST C. F. BARTH.
